UNITED STATES PATENT OFFICE.

GEORGE HUBERT RIVES, OF NEW YORK, N. Y.

DEVICE FOR FACILITATING THE DEALING OF CARDS.

No. 922,954.

Specification of Letters Patent.

Patented May 25, 1909.

Application filed September 22, 1908. Serial No. 454,133.

To all whom it may concern:

Be it known that I, GEORGE H. RIVES, a citizen of the United States, residing in the city, county, and State of New York, have 5 invented a new and useful Device for Facilitating the Dealing of Cards, of which the following is a specification.

My invention consists of a device or implement for facilitating the dealing of cards, 10 turning and moving leaves, sheets, etc., counting bank notes, etc., the same embodying a frictional or engaging surface, and a holder for the same applicable to a thumb or finger, said surface being removable from 15 said holder, and the latter being provided with members for securely retaining the surface in position thereon, said surface being adapted to be brought into contact with the cards, leaves, sheets, notes, etc., and take 20 sufficient hold thereon to move the same for the respective purpose thereof, while the surface may be removed, replaced, or substituted by another of different nature.

For the purpose of explaining the invention, 25 the accompanying drawing illustrates a satisfactory reduction of the same to practice, but the important instrumentalities thereof may be varied, and so it is to be understood that the invention is not limited to 30 the specific arrangement and organization shown and described.

Figure 1 represents a perspective view of a device embodying my invention. Fig. 2 represents another perspective view of the same 35 in operative position. Fig. 3 represents a side elevation thereof. Fig. 4 represents a side elevation of a portion of the device, a certain member being in different position from that shown in Fig. 3. Figs. 5 and 6 40 represent face views of other forms of frictional surfaces that may be employed.

Similar letters of reference indicate corresponding parts in the figures.

Referring to the drawings:—A designates 45 a band of elastic or pliable metal or other material, which is bent so as to embrace a thumb or finger of the operator of the device after the manner of a ring, the ends B, B, of which are separated so that the ring may be 50 readily adjusted in position and be adapted for thumbs or fingers of different thicknesses or sizes.

The exterior of the body of the ring has 55 thereon the facing piece C of soft rubber or other suitable material, the same following the contour of the exterior of said body and

so in a manner harmonizing with the contour of the inner face of the thumb or finger, said piece being removably held in position by the clamps D, which are mounted on the ears 60 E, the latter extending integrally from the body of the ring near the ends thereof, said clamps being each composed of an elbow-shaped member with the axes or journals F at the angle thereof, one limb G of said member being adapted to engage the adjacent end of the piece C and force it tightly against the body of the ring, thus controlling said piece in position, the other limb H serving to operate the limb G, whereby the clamp may 70 be turned on its axes so as to force the limb G into engagement with the facing piece C to hold it firmly on the body of the ring, the clamp thus retaining its position somewhat after the manner of an eccentric, as most 75 plainly shown in Fig. 3. When, however, the limbs H are forcibly thrown upward, the holding power of the limbs G on the piece C is released, and said limbs clear said piece, as shown in Fig. 4, when the piece may be removed for any purpose requiring the same.

It will be seen that when the device is applied to a thumb or other finger, it retains 80 its position thereon, after the manner of a ring, the facing piece C presenting itself on 85 the inner side of said thumb or finger, whereby when the device is presented to a pack of cards, sheets or leaves of papers or books, bank notes, etc., the piece C contacts 90 with the upper card, sheet, leaf, note, etc., and by movement of the hand, said card, etc. follows the same without slipping owing to the frictional contact of the piece with said card, etc., thus facilitating the dealing of the cards, the turning of the leaves of the book, 95 the distribution of the sheets of papers, the counting of the bank notes, etc.

In Figs. 1, 2, 3 and 4, I show the exterior surface of the piece C as corrugated. In Fig. 5, the same is roughened, and in Fig. 6, 100 said surface is provided with small points, such as pins or needles, but to these features, I do not limit myself, as any form of construction adapted to frictionally engage with a card, leaf, sheet, note, etc. and move the 105 same laterally from its fellows when the hand is properly manipulated, is within the scope of my invention, neither do I limit myself to material, as soft rubber, celluloid, metal and the like may be employed for my purpose, 110 producing substantially the same results; it being noticed also that the ring occupies but

a small portion of the thumb or finger, leaving the tip of the latter free to engage the card, leaf, etc., and so assist the piece C in its operation of dealing of cards, counting 5 money, etc., while the sense of touch of the thumb or finger is preserved as essential, especially in handling and counting bank notes for detecting counterfeits thereof, and a pen or pencil can be held and used while the 10 device is in position.

Having thus described my invention, what I claim as new and desire to secure by Letters Patent, is:—

1. A device for the purpose stated composed of a ring-like band, applicable to a thumb or finger, a frictional facing piece on the exterior of said band and following the contour thereof, and means carried by said band adapted to engage opposite ends of 20 said piece for firmly holding the same thereon.

2. A device for the purpose stated composed of a ring-like band applicable to a thumb or finger, a frictional facing piece on 25 the exterior of said band and confined within the width thereof, said facing piece being disposed in parallel relation with and following the contour of the band for a major portion thereof, and means on said band engaging opposite ends of and removably holding said piece thereon.

3. A device for the purpose stated composed of a ring-like band applicable to a thumb or finger, a frictional facing piece on 35 the exterior of said band and confined within

the width thereof, said facing piece being disposed in parallel relation with and following the contour of the band for a major portion thereof, and clamps on said band engaging the ends of and removably holding said piece 40 thereon.

4. A device for the purpose stated composed of a ring-like band applicable to a thumb or finger, a frictional facing piece on the exterior of said band following the contour thereof and extending for a major portion thereof, and clamps carried by the band and movably mounted and having members adapted to engage said piece and hold it firmly on said band. 45

5. A device for the purpose stated composed of a ring-like band applicable to a thumb or finger, a frictional facing piece on the exterior of said band, rotatably movable clamps having members adapted to engage 55 said piece, and means on said band adapted to form the bearings of said clamps.

6. A device for the purpose stated composed of a ring-like band applicable to a thumb or finger, a frictional facing piece on 60 the exterior of said band, rotatable clamps adapted to engage said piece and tighten it on said band, bearings on said band for said clamps, and members on said clamps adapted to operate the latter in opposite directions. 65
